UNITED STATES PATENT OFFICE.

ANDEAN W. WHITEMAN, OF SAN FRANCISCO, CALIFORNIA.

PAPER-HANGER'S BUCKET AND BRUSH STAND.

Application filed August 9, 1927. Serial No. 211,768.

This invention relates to an improved stand especially constructed to accommodate and support a paper hanger's paste bucket and brush.

5 The invention has more particular reference to a metallic stand of a foldable nature which is especially designed for supporting a bucket of paste in an upright position, and for maintaining a complementary brush in a 10 convenient position for ready use.

The structure is designed to be used in connection with the ordinary or conventional papering trestle or table.

Briefly, the invention comprises a stand 15 which includes a pair of pivotally connected crossed legs having their upper ends formed into standards provided with opposed complementary members for embracing the mouth of the bucket.

20 A special prop is associated with the pivoted portion of the legs and a latch is also employed here to aid in maintaining the stand in supporting position.

Mounted on the stand on one side is a brush 25 supporting shelf.

In the drawings:—

Figure 1 is a perspective view of a stand constructed in accordance with the invention, showing the same set up for use.

30 Fig. 2 is also a perspective view showing the stand folded for carrying.

As before indicated, the stand includes a pair of legs 3 which are disposed in crossed or intersecting relation and then pivotally connected together. The lower ends of the 35 legs are fashioned to rest upon the floor or other supporting surface.

The upper ends of the legs are constructed to provide a pair of standards 4 at the upper 40 ends of which are semi-circular bands 5 arranged in opposed spaced relation to provide a sectional annulus to embrace the bucket. Incidentally, the bucket is seated in between bands 5, the standards 4, and rests upon the 45 upper end portions of the legs 3.

Fastened to the legs is a prop generally 50 designated by the reference character 6. This comprises a pair of pivotally connected feet 7 connected with the intersecting portions 55 of the legs, through the medium of an appropriate connecting member 8. Incidentally these feet are disposed at right angles to

the legs 4 in order to provide a four-point rest, or base for the stand.

To aid in maintenance of the stand in opposite positions, I prefer to provide a pivoted latch 9 which has its lower end portion twisted as at 10 and notched to engage one of the legs in the manner shown in Fig. 1.

This complementary leg is also provided 60 with a notch to cooperate with the latch. Attention is now invited to a pan-like brush receiving shelf 11 fastened to one of the shanks. A strap 12 is fastened to the under side of this shelf and includes depending portions 13 and 14. The free end of the portion 14 is formed with a notch engaging the standard as shown in Fig. 1. Also, the inner end portion of the strap 12 is twisted and connected with a corresponding twisted bracket 15 70 riveted to the upper end of this same strap.

It will thus be seen that a pivotally mounted shelf is provided together with a brace for holding the shelf in horizontal brush supporting position.

75 A device of this kind is particularly advantageous in that it serves to support the paste bucket at an elevation to overcome frequent dipping, such as is necessary in applying the paste in the ordinary method. This 80 of course holds the brush in a convenient position, so that it can be picked up and laid down at frequent intervals to save time, in case the customary way of laying the brush on the table or laying it in some out of the way 85 place.

These and other advantages and features have doubtless been made apparent from the following description and drawings, for which reason a more lengthy description is 90 thought unnecessary.

Changes in shape, size, and re-arrangement of parts coming within the field of invention claimed may be resorted to if desired.

Having thus described my invention, what 95 I claim as new is:—

1. In a structure of the class described, a stand comprising a pair of pivotally connected crossed legs, standards rising from said legs, semi-circular bands at the upper ends of said standards, forming a split annulus for surrounding a receptacle, and a prop 100 associated with the crossed portions of said legs.

2. In a structure of the class described, a stand comprising a pair of pivotally connected crossed legs, standards rising from said legs, bucket embracing means on the upper ends of said standards, a prop comprising a connecting member and a pair of pivotally-connected feet carried thereby, said feet be-

ing disposed at right angles to said legs, a latch pivotally connected with one of the legs and cooperating with the remaining leg for maintaining said legs in supporting position.

In testimony whereof I affix my signature,

ANDEAN W. WHITEMAN.
